UNITED STATES PATENT OFFICE

108,028

DESIGN FOR A VEGETABLE MASHER OR SIMILAR ARTICLE

Joseph G. Jackson, Oak Park, Ill., assignor to
The Edward Katzinger Company, Chicago, Ill.,
a corporation of Illinois

Application January 22, 1937, Serial No. 67,235

Term of patent 14 years

To all whom it may concern:

Be it known that I, Joseph G. Jackson, a citizen of the United States, residing at Oak Park, in the county of Cook and State of Illinois, have invented a new, original, and ornamental Design for a Vegetable Masher or Similar Article, of which the following is a specification, reference being had to the accompanying drawing, forming part thereof.

Fig. 1 is a perspective view of the vegetable masher or similar article, showing my design; and

Fig. 2 is an enlarged bottom plan view of the blade portion thereof.

I claim:

The ornamental design for a vegetable masher or similar article, as shown.

JOSEPH G. JACKSON.
